[57] CLAIM

The ornamental design for a cage for a chromatography
fused-silica capillary column, as shown and described.

DESCRIPTION

FIG. 1 is a top front perspective view of a cage for a
chromatography fused silica capillary column;

FIG. 2 is a front elevation thereof;

FIG. 3 is an elevation taken 90° from FIG. 2;

FIG. 4 is a bottom plan view thereof; and,

FIG. 5 is a top plan view thereof.
